CLAIM

The ornamental design for a glare reducer for attachment to a window of a vehicle, as shown.

DESCRIPTION

FIG. 1 is a front elevational view of a glare reducer for attachment to a window of a vehicle showing my new design, it being understood that the rear elevational view is a mirror image thereof;

FIG. 2 is a top view of the glare reducer of FIG. 1;

FIG. 3 is a bottom view of the glare reducer of FIG. 1;

and,

FIG. 4 is a right side view of the glare reducer of FIG.

1.
